UNITED STATES PATENT OFFICE

JOHN E. CARR AND JOHN KNELL, OF AURORA, ILLINOIS, ASSIGNEES TO ALL-STEEL-EQUIP COMPANY, A CORPORATION OF ILLINOIS

LOCK MECHANISM

Application filed May 1, 1930. Serial No. 448,907.

This invention relates to a lock mechanism particularly adapted for use in lockers, and has among its principal objects to provide a construction which is extremely simple in its arrangements and parts; which reduces the number of parts to a minimum; which may be inexpensively manufactured; and which is sturdy, reliable and theft-proof.

Other and further objects and advantages will become apparent as the disclosure proceeds and the description is read in conjunction with the accompanying drawings, in which

Fig. 1 is a front, elevational view of a locker embodying one form of this invention;

Fig. 2 is a view showing a fragment of the door panel with the handle and lock cut away to expose the slotting of the panel;

Fig. 3 is a vertical, sectional view taken on the line 3—3 of Fig. 1;

Fig. 4 is a transverse, sectional view taken through the lock and corner post on the line 4—4 of Fig. 1;

Fig. 5 is a perspective view of the lock plug head;

Fig. 6 is a transverse section of a door and corner post embodying a modified form of this invention, the lock in this case being secured to the door panel;

Fig. 7 is a vertical, sectional view of the same, the section being taken on the line 7—7 of Fig. 6;

Fig. 8 is a vertical, sectional view of the embodiment shown in Figs. 6 and 7, taken on the line 8—8 of Fig. 6;

Fig. 9 is a view corresponding to Fig. 6 and represents still another embodiment of this invention; and

Figs. 10 and 11 are sectional views taken on the lines 10—10 and 11—11, respectively, of Fig. 9.

But these specific illustrations and the corresponding specific descriptions are for the purpose of disclosures only for it is realized that the latch mechanism may be embodied in other relations and in other forms without departing from the spirit of this invention.

A conventional sheet metal locker has been chosen to illustrate one application of this invention, and comprises a steel frame

having angle uprights 10, 11 and cross channels 12, 13. A door 14 is hinged at 15 to the upright 11 and is adapted to be closed flush with the front webs of the angle uprights 10, 11. The edges of the door are turned inwardly at 16 and again at 17 to form a U-shaped reinforcing flange or channel.

Slidably mounted within the channel at the free edge of the door is a latch bar 18 cut from a flat strip of stout metal. Catches 19 are riveted to the bar at suitable intervals and pass through elongated slots 20 in the wall 17 of the flange. Preferably, the heads of the catches are tapered to a blunt point, and notches 21 are cut into their lower edges.

A door jamb 22 is riveted or otherwise secured to the front web of the angle upright 10 and is provided with a plurality of lugs 23 extending parallel to the plane of the door and occurring at intervals corresponding to the catches on the latch bar.

A handle 24 is riveted to the latch bar at 25, the arms passing through slots 26 in the door panel. The handle is cast with an enlarged boss 27 at one end, in this case the upper end, and is bored at 28 to receive a lock plug 29 of a tumbler lock. The lock plug is of general cylindrical form but the head is split along its axis at 30 for a short distance and then squared off at 31, thus forming a shouldered semi-cylindrical head.

An irregularly shaped slot 32 is stamped from the door panel and merges with one of the slots 26. The shape of this slot is shown in Fig. 2 and is adapted to receive the semi-cylindrical head of the lock plug. The slot is so shaped that when the catches on the latch bar are in engagement with the lugs 23 of the door jamb, the lock plug may be rotated to a position which will bring the face 30 of the head beneath a shoulder 33 of the slot, thus preventing the bar from being raised to open the door. The curved wall 34 of the slot accommodates the correspondingly curved surface of the lock plug head.

When the plug is rotated in a clockwise direction (Fig. 2) through 90°, the face 30 strikes the wall 35 and alines the plug head in the slot and permits the latch bar to be

raised and the door opened. Inasmuch as the rotation of the lock plug is limited to 90°, the insertion and withdrawal of the key 36 is greatly facilitated.

5 Referring now to Figs. 6 to 11 inclusive, there are illustrated two other forms of latch mechanisms, each of which has a stationary lock, that is a lock secured to the door panel and engaging the latch bar to lock the same against movement.

10 In the embodiment shown in Figs. 6, 7 and 8, a latch bar 37 is slidably mounted within the U-shaped channel at the free edge of the door and differs only from the latch bar 18 in that it is bowed at 38 and provided with a notch 39 cut from one side of the bar. The lock in this case is secured to the door panel preferably above the handle, in all other respects, however, being similar to the lock 25 already described.

20 When the catches on the latch bar are fully seated upon the door jamb lugs, the notch 39 is opposite the lock plug head, which may be rotated to the position shown in full lines 25 in Fig. 7 to lock the bar against movement.

25 To open the door, the plug is rotated to the position shown in dotted lines in the same figure, and the bar is then free to be raised.

30 In this embodiment, also, it will be noted that the parts cooperate to limit the rotation of the plug to a given angle so that the key 36 may be readily inserted and withdrawn.

35 In place of a bowed latch bar, a latch bar 40 may be substituted having a finger 41 punched from one edge and adapted to engage the lock plug head when the face 30 is in a horizontal position. When the lock plug is rotated to the position shown in dotted lines, Fig. 10, the latch bar is free from obstruction and the bar may be raised or lowered as desired. Since the tip of the finger 41 lies in a vertical plane, the plug can only be 40 rotated through 90 degrees.

45 It will be understood that the invention is not limited to the particular form of lock plug head shown in the drawings and herein described, the gist of the invention being to provide a lock plug having an eccentric longitudinal projection and adapted to interlock 50 with some relatively fixed or movable part, as the case may be, to lock the bar against movement.

We claim:

55 1. In a device of the class described, a door including a front panel member, a latch bar member movable with respect to the door, a handle rigidly secured to the bar, means to lock the latch bar against movement including a rotatable key plug having a semi-cylindrical head having a radius not greater than that of said plug, said head being directly engageable with an integral portion of one 60 of said members.

65 2. A latch mechanism for locker doors comprising in combination a movable latch bar,

a lock plug having a semi-cylindrical locking head directly engageable with the latch bar to lock the latch bar against movement.

3. A latch mechanism for locker doors comprising in combination, a movable latch bar, a rotatable lock plug having an eccentric, longitudinal projection, and a shoulder on the latch bar formed by stamping out a piece therefrom adapted to interlock with the plug projection when the latter is in a given position to lock the bar against movement, said plug being rotatable to some other position, whereby the bar can be moved to unlatch the door.

4. In a latch mechanism for locker doors, comprising in combination a movable latch bar, means for locking the latch bar against movement, including a lock plug having an eccentric longitudinal projection directly engageable with the latch bar, and a shoulder on the latch bar formed by stamping out a piece therefrom for limiting rotation of the lock plug to a given angle.

5. In a device of the class described, a door provided with an elongated slot having an enlargement at one end, a latch bar movable with respect to the door, means to lock the latch bar against movement including a rotatable lock plug movable with the latch bar, said plug having a semi-cylindrical head adapted to coact directly with the slot and hold the latch bar against movement when the plug is in one position, but permitting the latch bar to be moved when the plug is 95 in another position.

In testimony whereof we affix our signatures.

JOHN E. CARR.
JOHN KNELL.
